DESIGN FOR A CABINET FOR A COMBINATION FIREPLACE AND DINETTE

Bernard D. Colen, Great Neck, N. Y., assignor to Colen-Gruhn Co. Inc., New York, N. Y.

Application June 1, 1936, Serial No. 62,931

Term of patent 7 years

To all whom it may concern:

Be it known that I, Bernard D. Colen, a citizen of the United States, residing at Great Neck, in the county of Nassau and State of New York, have invented a new, original, and ornamental Design for a Cabinet for a Combination Fireplace and Dinette, of which the following is a specification, reference being had to the accompanying drawing, forming a part thereof.

for a combination fireplace and dinette showing my new design.

Fig. 2 is a side elevational view thereof.

I claim:

The ornamental design for a cabinet for a combination fireplace and dinette as shown.

In testimony whereof I have signed this specification.

BERNARD D. COLEN.
